FASTENER FEED MEANS FOR FASTENER DRIVING DEVICES

Joseph C. Lang, Pittsburgh, Pa., assignor to Bocjl Corporation, Pittsburgh, Pa., a corporation of Delaware

Original application December 12, 1945, Serial No. 634,537, now Patent No. 2,580,444, dated January 1, 1952. Divided and this application December 31, 1951, Serial No. 264,294

5 Claims. (Cl. 1—51)

This invention relates to the art of fasteners and is for a driver for driving a succession of fasteners one at a time.

I have heretofore devised a tack type of fastener of tack-like form, this fastener having a cross bar forming the head, and having a shank which is turned down at one side of the cross bar intermediate the ends thereof. An especial advantage of this T-tack, aside from the fact that it provides a very effective tack for upholstering and other purposes because of the long head which will not pull through the fabric or other material which is fastened down, is that a succession of tack blanks may be economically formed from a narrow ribbon of rolled metal. This is done by slitting the metal diagonally from one edge toward the center and then extending the slit longitudinally, preferably along the center line, for the length of the leg. A small fraction of an inch past the end of this slit the next similar slit is formed. Thus a succession of leg portions are provided which are separated from the ribbon of metal at the other side of the center line throughout their length at one point only, the diagonal slit forming a point on the free end of each leg portion. By turning the legs so formed from their original plane through an arc to a position perpendicular to said plane, each leg is then in position to be driven. The continuous ribbon of metal at the other side of the center line is severed at points intermediate the diagonal slits transversely of the long axis of the ribbon to form individual complete tacks. All of this is disclosed in a copending application filed by me.

The object of the present invention is to provide a convenient, compact and novel driver for receiving a roll of metal so slotted and feeding it to a driver, the leg forming portions being successively turned down into perpendicular position, the machine severing the successive blanks and driving the completed tacks. Thus instead of requiring a mass of loose tacks which must be individually formed, individually handled and driven, the machine of the present invention requires only a roll of the prepared strip or wire, converting this slotted strip into tacks along with the operation of driving. This is important in many industries also from the health standpoint in that it eliminates "spitting" the tacks, i. e., the practice of holding a number of tacks in the mouth and removing them one at a time. It is not only more desirable from a health angle, but a worker can operate faster, position the tacks more accurately, and avoid possible minor injury from the hitting of the fingers. Incidentally, also, it saves nicking and marring furniture to which upholstering is being applied by avoiding the frequent hitting of the finished woodwork by the upholsterer's hammer.

A further object of the present invention is to provide a novel mechanism for indexing and feeding the fastener strip through the machine, the feed mechanism engaging notches in the edge of the strip of connected fastener blanks.

This application is a division of my copending application Serial No. 634,537, filed December 12, 1945, and issued as U. S. Letters Patent No. 2,580,444 on January 1, 1952.

My invention may be more fully understood by reference to the accompanying drawings, in which:

Fig. 1 is a side elevation of a fastener driving machine embodying my invention;

Fig. 2 is a fragmentary section in the plane of line II—II of Fig. 1, the view being a transverse horizontal section;

Fig. 3 is a side elevation of that portion of the cover plate which extends along the bottom of a machine, and which is broken away in Fig. 1;

Fig. 4 is a view similar to Fig. 1, showing the entire cover plate removed from the machine;

Fig. 5 is a horizontal section in substantially the plane of line V—V of Fig. 1, looking up, the view being a fragmentary view;

Fig. 5a is a transverse section in the plane line V^a—V^a of Fig. 7, looking down;

Fig. 6 is a fragmentary side elevation similar to a portion of Fig. 4, but with the driver element depressed to the full limit of its movement;

Fig. 7 is a transverse vertical section in substantially the plane of line VII—VII of Fig. 1;

Fig. 8 is a schematic view showing the initial step in beginning the operation of the driver with a new strip of fasteners;

Fig. 9 is a similar view showing the succeeding step; and

Fig. 10 is a view similar to Fig. 8 showing the operation which follows after the first one.

In the operation of the machine as hereinbefore indicated, a strip of connected fastener blanks is utilized. This strip is best shown in Figs. 5, 8, 9 and 10, and is the subject of a copending application. The strip comprises a continuous ribbon or narrow flat strip of metal designated generally as A. This ribbon has a succession of regular spaced notches a along one marginal edge, the forward wall of these notches being perpendicular and the other wall being sloped so as to cooperate with correspondingly shaped pawl or ratchet teeth to be hereinafter described. The opposite edge of the strip is slit diagonally from the edge toward the center, and then the slit extends in a longitudinal direction. With reference to the direction in which the strip travels through the driving machine, the longitudinal portion of the slit extends rearwardly from the diagonal portion. In the drawings the diagonal portion of the slit is designated a¹ and the longitudinal portion is designated a². The slit a² separates the leg forming portion a³ of the strip from the body of the strip, the diagonal slit a¹ separating the leg at one end and forming the point of the fastener. The notches a along one edge of the strip are preferably staggered with reference to the slits a¹ and also define the points along which the ribbon is separated in forming the individual fasteners.

As shown in Fig. 8, the front end portion of the strip has the leg-forming element cut away so that on the first operation with each strip, an incomplete fastener is formed. This is for the purpose of enabling the strip to be properly handled in the machine, and indexing the strip for its initial operation.

In completing the fastener, the leg-forming portion a³ must be swung in an arc about an axis transverse to the length of the strip downwardly to a perpendicular position and then the strip is severed and the blank which has been so formed is driven into the material into which it is to be entered.

In the present machine, with the first operation of the driver or plunger which serves to drive the staple, the blank head having no attached leg portion, which forms the leading end of the strip, is removed. This is shown in Fig. 9 where the detached head portion is designated a⁴ and the succeeding head portions are designated a⁵. In severing the incomplete blank as shown in Fig. 9, the leg-forming portion a³ of the succeeding blank is bent down to the perpendicular position. With the further operation of the machine, the strip feeds forward the full length of one blank, i. e., the distance between successive notches a. On the succeeding operation this blank with the turned down leg is then driven as shown in Fig. 10 and the leg-forming portion a³ of the next succeeding blank is simultaneously turned down. This sequence of operations follows thereafter during the continued operation of the machine until the length of the staple strips has been exhausted. Thus with each driving operation one blank with the bent-down leg is

70
75
80

separated from the strip and driven while the leg-forming portion of the next succeeding blank is bent down, and at the time that the driver raises above the fastener strip, the strip advances one notch, or the length of one blank, to bring the next succeeding blank, the leg of which has been turned down, into position under the driver.

With this general explanation of the operations which take place, the construction of the machine may now be easily understood.

Referring to the drawings, the machine comprises a frame construction providing at its forward end a vertical slide-way in which a reciprocating plunger operates. This plunger, designated generally as 2 in Fig. 1, has a terminal 3 at its upper end which may be hit with a hammer in a portable machine, or which may be depressed by any suitable impact mechanism when the unit is incorporated in a non-portable or portable power operated machine. At the opposite end of the frame the construction provides a circular chamber designated generally as 4 for receiving the fastener strip which is coiled up within it, the convolutions of the coil of the strip being designated generally as A'. Intermediate this chamber or magazine portion and the forward portion which houses and provides a slide for the plunger, there is a connecting body having an opening 5 therethrough with a cross bar 6 above the opening, the under side of the cross bar being preferably scalloped to provide a convenient grip for the fingers of the operator, while the opening 5 provides clearance for the fingers.

The frame of the machine is formed by one main plate, designated generally as 7, and which is best shown in Fig. 4. The main plate 7 is preferably formed as a casting with the opening 5 formed therethrough, and with a part 6' forming part of the grip 6. At one end it is provided with an upstanding flange 8 of generally circular contour. Within this circular flange 8 there is cast an upstanding hub (see Fig. 2) 9. This hub 9 serves to rotatably support a removable flanged spool or sleeve 10 on which the convolutions of the fastener strip A' are wound. Extending forwardly under the open portion 5 the main casting is provided with a flat panel or surface 11 on which a block 12 carrying the strip feeding mechanism is removably secured. At the forward or left-hand end of the casting, as viewed in Fig. 4, there is a vertical portion 13 in which the plunger 2 is received.

The casting is provided with a number of screw holes which are threaded to receive screws 14 which hold a complementary cover plate 15 in place. The cover plate 15 is of less extent than the main casting 7 and serves to cover only the front or left-hand portion of the main casting together with part of the feeding mechanism, and extends back only to the magazine-forming part of the machine. This cover plate does not normally have to be removed, being formed in the manner described only for convenience in assembly, and to provide access to the interior of the machine for purposes of replacement or repair of parts.

There is a second cover plate designated generally as 16 which is preferably stamped from sheet metal, and which is readily removable to give access to the magazine for the replacement of the staple strip and give access to that portion of the feeder through which the strip moves for threading the strip into the machine. This cover part has a generally circular end portion 16a which encloses the chamber 4 of the magazine, and it has a forwardly extending portion 16b that extends horizontally under the lower edge of the cover plate 15, covering the lower portion of the feeder to be herein-after described. As shown in Fig. 3, the extreme forward end of this extension 16b has a tongue 16c thereon, which, as indicated in dotted lines in Fig. 1, extends under a part of the cover plate 15 to hold this narrow horizontal extension of the cover plate in place.

For detachably holding the cover 16 in position, a screw 17 passes through the hub portion 9 and through a central opening in the cover plate 16. Threaded onto this screw is a nut 18 having a radial extension 19. The cover plate 16 has a slot 20 therein extending outwardly from the opening through which the screw 17 passes. To remove the cover plate 16 it is merely necessary to turn the nut from the position shown in Fig. 1 to a position where the extension 19 is in line with the slot 20, at which time the nut will be ineffective to hold the cover plate in place, and it may be removed by lifting it away from the machine. When it is lifted away so that the

cover plate 16 entirely clears the nut 18 with its extension 19, the cover plate 16 may be slid rearwardly until the tongue 16c is clear of the part of the machine with which it is engaged. Thus the cover plate 16 can be very quickly removed, and it can be reapplied with equal facility by merely engaging the tongue in its proper place, swinging the circular end of the cover back in position over the magazine, allowing the slotted opening to pass over the key nut, and then tightening the nut down on the screw.

The foregoing description relates to the general organization of the machine which is the present preferred embodiment, but it will be understood that this is merely illustrative of the machine. The mechanisms for driving the fasteners and feeding the strip may now be described in detail. The plunger 2 has laterally-extending flanges 2a at each side of its forward edge, these flanges being guided in channels 2c formed in the main casting, and the forward part of the fixed cover plate 15, as best shown in Fig. 5. Near the lower end of the plunger or driver is a rearwardly-extending cam 21, the effective surface of which is designated 22, and which slopes upwardly and rearwardly as viewed in Fig. 4.

Below this cam the plunger is provided with a terminal portion adapted to perform the operations hereinbefore described. The terminal portion includes an offset tongue 23 (see Figs. 8, 9 and 10) for engaging the leg-forming portion of the fastener and bending it downwardly, this portion also being shown in Fig. 4. It is to the rear and offset from the main driving tongue 24 which has a rib 25 on one surface thereof. It is adapted to apply pressure to the head of the fastener while the rib 25 is adapted to be directly over the leg and apply pressure likewise to the leg of the fastener. The tongue 24 projects downwardly a distance substantially below the tongue 23. It should also be mentioned that the rear corner designated 24a of the tongue 24 forms one element of a shear for cutting off the formed blank from the strip.

The plunger is also provided intermediate its ends with notches 26 and 27 between which are serrations 28 (see Fig. 4) for cooperation with a spring-centered pivoted pawl 29. The purpose of this pawl is to prevent the plunger or driver from moving in either direction unless its full stroke in the opposite direction is completed. This is a well-known mechanism in movements of this kind, and constitutes no part, per se, of the invention. The plunger carries a headed bolt 30 on its rear face which forms an abutment to limit the upward travel of the plunger, and a tension spring 31 (see Fig. 7) connected between a pin 32 on the plunger and a fixed anchorage 33 on the cover plate 15 serves to return the plunger to the uppermost position shown in Fig. 4 after the plunger has been driven downwardly.

As hereinbefore mentioned, the part 11 of the main plate carries a foundation plate 12 on which the strip feeding mechanism is mounted. The plate 12 is of a thickness somewhat greater than the width of the fastener strip. It is provided with a groove 34 along its entire length, this groove being open on that face of the plate 12 which is turned toward the removable cover 16. The depth of the groove is equal to the full width of the fastener strip A, and the width of the groove is just slightly greater than the thickness of the strip A so that as shown in Figs. 4, and 5, the end of the strip may be entered in the rear or right-hand end of the groove as viewed in Fig. 4 and the strip pushed forward until the forward end of the strip is under the tongue 24 of the driver. The strip is inserted in the machine so that the edge containing the notches a are turned outwardly, that is, toward the open edge of the groove 34.

Mounted on the lower portion of the block 12 is a U-shaped piece 35 with the legs of the U turned upwardly and extending across the slot 34. On top of the U-shaped piece 35 is a U-shaped flat spring 36 having arms 37 that overlie the upwardly-extending arms of the U-shaped piece 35. There are pins 38 on the arms 37 of the spring, which pins slidably pass through the arms of the piece 35, and as shown in Fig. 5, press into engagement with the notches a in the fastener strip. These pins are in the shape of pawls having a square forward face and a rearwardly sloping face. As is clearly evident from Fig. 5, these pins enable the strip to be pushed forwardly through the groove 34, but they spring into the notches and acting as pawls to prevent movement of

strip in the opposite direction. Once the strip has been engaged with the spring pressed pins or pawls 38, it cannot be pulled backwards.

Mounted on the plate 12 above the slot 34 is a slide plate 40 having a slot 41 through which passes a fixed guide pin 42. The slide plate 40 also has two other slots 43 through which pass guide pins 44. Tension springs 45 are stretched between the fixed pins 44 and anchor pins 46 on the slide. The purpose of these springs is to urge the slide plate 40 toward the left as viewed in Fig. 4. This slide plate has a cam engaging roller 47 at its upper forward corner which bears against the sloping cam surface 22 on the plunger and which is urged into engagement against this cam surface by the springs 45 which pull the slide toward the left as viewed in Figs. 4 and 6.

When the plunger 2 is depressed, the cam 22 engaging the roller 47 forces the slide plate 40 toward the right as viewed in Fig. 4. When the plunger moves upwardly, the springs 45 serve to return the slide plate to the position shown in Fig. 4. This motion is clearly shown in Fig. 6, where the plunger is in its lowermost position and the roller 47 is at the end of the cam 22.

The slide plate 40 has two downwardly-extending arms 48 that also extend over the groove 34. There is an inverted U-shaped flat spring 49 on the slide plate 40 having arms 50 thereon. These arms carry pawl-like pins 51 similar in all respects to the pins 38 on the fixed spring 36. When the slide 40 is cammed back, the pins 51 ride out of the notches, and along the edge of the strip, the resilience of the arms 50 permitting the pins to yield. When, however, the slide 40 comes forwardly, the pins 51 will catch in the notches *a* on the strip and feed the strip forwardly.

Thus with each operation of the plunger downwardly, the slide 40 moves back while the fixed pins 38 prevent the strip from moving back, and on the return movement of the slide 40 when the plunger raises, the strip is advanced.

As shown in Figs. 5 and 5a, the plate 12 extends forwardly to the front of the housing and there is an opening 53 in the housing through which the strip may be pulled, should it be defective. One surface of the plate 12 provides a shoulder 52 against which the downwardly-turned leg of a fastener abuts, as the strip is fed forward, thus providing both an indexing stop and a guide for two surfaces, that is, one face and one edge of the leg of the fastener. The leg, being thus confined, is supported along with the additional support hereinafter described, against buckling. When the strip A is shoved into the machine, the leading edge of the strip is under the tongue 24 of the driver. The first blank end is cut off, and on the next feeding of the strip, the leg portion of the succeeding blank engages shoulder 52 to limit the strip.

For initially supporting the leg on its other two sides during the beginning of the driving operation, there is, in the lower part of the housing, a transversely movable guide block 55 (see Fig. 7) with a notched toe 56 that is beveled on its upper edge, this block having a hollow extension 57 that is slidably guided in a bushing 58 threaded into an opening in the lower part of the cover plate 15, and a spring 59 is operatively interposed between the bushing and the extension. The toe of the block is normally positioned in spaced relation to the rear of shoulder 52, so that the leg of the tack, when the tack is driven, is between the toe 56 and the shoulder and the edge of the leg between the block 55 and the face of the plate 12. The top of the guide block is beveled at a steep angle, so that when the lower end of the driver hits this surface, the block will be pushed back, i. e., toward the left as viewed in Fig. 7, to allow the driver to come down until its end is about flush with the bottom of the machine. However, at the time the guide block is pushed back, the fastener will have penetrated part way into the substance into which it is driven, and the leg will be unsupported by the toe only in the final stages of driving, at which time the short undriven length needs support no longer.

When the driver raises, the guide block springs back into position. It should be noted in Fig. 7 that the beveled surface of the guide block is below the point of the leg of the fastener next succeeding, so that the guide block offers no obstruction to the advancing of the strip of fasteners.

The supporting plate 12 has a hardened steel block 60 secured thereto with the top of this block forming an

extension of the lower side of the groove 34. The upper forward corner 61 of this block just clears the shoulder or corner 24a of the driver, forming the other jaw of the shear for severing the fastener to be driven from the strip.

The lower end of the driver may, as shown in Figs. 4 and 6, project down further at the edges than at the center, so that when the fastener is being set at the end of the driving operation, the two ends of the cross bar forming the head of the fastener will be pressed down and eliminate any tendency for them to spring up. One of these projections, previously referred to, is marked 24a and the other is designated 24b in Fig. 4.

In operation, assuming a strip of fasteners to have been entered in the machine, the first head of the strip will have no leg-forming portion (see Fig. 8). The strip will be pushed through until this end is under the driving plunger. Then the plunger is operated. The incomplete blank is sheared off and driven down. As the driver moves past shearing position tongue 23 on the driver, offset as it is to engage only the leg-forming portion, bends the leg of the next succeeding blank down, as shown in Fig. 9. During the down travel of the plunger feeder plate 40 is cammed to the right as viewed in Fig. 4. Then the plunger raises. Springs 45 pull the feed plate to the left, advancing the fastener strip until the newly sheared end hits the shoulder 53 (see Fig. 5). On the next operation of the plunger, the driver tongue 24 cuts off the second blank with its now depending leg, drives it, and the leg portion of the next blank is at the same time turned down.

It will be observed in Fig. 6 that when the slide plate is cammed back and the fastener cut-off on the down stroke of the plunger, the end of the strip bears against the rear edge of the tongue 24, so that when the plunger starts to move up, the strip cannot feed forward. Hence the cam may move up and disengage the roller 47 on the slide plate. Then when the end of the plunger clears the strip, the springs 45 act to snap the strip forward, giving a positive feed and driving the leg against shoulder 52 to make sure it is vertical and square against the guide shoulder. Thus the operation is repeated, a strip containing several hundred fastener blanks being accommodated in the machine.

The end of the driver guide may be shaped in various ways where desirable, to enable the driver to work in close to corners.

The strip feeding arrangement, cooperating with notches on the edge of the strip with the pawls working perpendicularly to the edge is of considerable importance in simplifying the feeding mechanism and making it compact and yet positive. If the feeding mechanism fails, the plate 12 with all of the feeder parts may be removed and replaced by a similar unit.

The machine provides a relatively simple, cheap driver, positive in its action for feeding, bending the legs, cutting off and driving the successive fastener blanks accurately, speedily, and easily.

While I have shown and described one preferred embodiment of my invention, it will be understood that various changes and modifications may be made therein.

I claim:

1. A fastener driving machine having a driver, a magazine for holding a coil of prepared flat strip with regular notches in one edge thereof, a reciprocable feeder positioned flatwise of the edge of the strip and in a plane at one side of the edge of the strip and having means thereon engaging the notches in the edge, for advancing the strip from the magazine to the driver, and means for reciprocating the feeder.

2. In a machine of the class described having a driving plunger and a magazine for holding a prepared strip with regular notches in an edge thereof, a feeder for moving the strip step by step to feed the end thereof under the driving plunger, the feeder comprising a slide plate perpendicular to the flat face of the strip, pawl means on the plate movable in a direction normal to the edge of the strip into and out of the notches, and means for operating the feeder in coordinated relation to movement of the plunger.

3. In a machine of the class described having a driving plunger and a magazine for holding a prepared strip with regular notches in an edge thereof, a feeder for moving the strip step by step to feed the end thereof under the driving plunger, the feeder comprising a slide plate per-

pendicular to the flat face of the strip; pawl means on the plate movable in a direction normal to the edge of the strip into and out of the notches; means actuated by the plunger for operating the feeder and detent means on the machine also movable in a direction normal to the edge of the strip for engaging the notches in the edge thereof and holding the strip against backward movement.

4. A machine of the class described having a channel for receiving a strip of fastener blanks in which one edge of the strip is provided with a succession of longitudinally extending leg forming elements and the other edge is provided with ratchet-like notches, the strip moving through the channel with the notched edge exposed at one side of the channel, feed means movable back and forth along the channel and engaging said notches in the edge of the strip in a direction normal to the edge of the strip for advancing the strip step by step, and means for imparting back and forth movement to said feed means.

5. A machine of the class described having a channel for receiving a strip of fastener blanks in which one edge of the strip is provided with a succession of longitudinally extending leg forming elements and the other edge is

5

10

15

20

provided with ratchet-like notches, the strip moving through the channel with the notched edge exposed at one side of the channel, a feeder movable back and forth along the notched edge of the strip having pawl elements therein for engaging said notches to advance the strip step by step, and other means engaging said notches in the strip for holding the strip against movement in one direction; and means for imparting a back and forth movement to the feeder.
